UNITED STATES PATENT OFFICE.

GREEN B. WILSON, OF NEVADA, IOWA

COOLED BLOWPIPE OR TORCH.

1,199,140.

Specification of Letters Patent. Patented Sept. 26, 1916.

Application filed April 5, 1916. Serial No. 89,140.

To all whom it may concern:

Be it known that I, GREEN B. WILSON, a citizen of the United States, residing at Nevada, in the county of Story and State 5 of Iowa, have invented a new and useful Cooled Blowpipe or Torch, of which the following is a specification.

The present invention appertains to blowpipes and torches, such as use acetylene gas 10 mixed with oxygen, and it is the object of the invention to provide novel and improved means for cooling the blowpipe or torch, and especially the tip thereof, to prevent the excessive heating of the device which is 15 objectionable for obvious and well known reasons.

The present invention embodies a fluid 20 circulating chamber inclosing the blowpipe or torch and extending to the tip thereof, whereby water, air or other suitable fluid 25 can be circulated through said chamber to produce the desired cooling effect.

It is also within the scope of the invention 25 to provide a cooled blowpipe or torch which is comparatively simple, compact and inexpensive in construction, as well as being thoroughly practical, efficient and reliable in use.

With the foregoing and other objects in 30 view which will appear as the description proceeds, the invention resides in the combination and arrangement of parts and in the details of construction hereinafter described and claimed, it being understood that 35 changes in the precise embodiment of the invention herein disclosed can be made within the scope of what is claimed without departing from the spirit of the invention.

The invention is illustrated in the accompanying drawing, wherein:

Figure 1 is a longitudinal section of the improved structure, portions being broken away and others being shown in elevation. Fig. 2 is an enlarged cross section on the 45 line 2—2 of Fig. 1. Fig. 3 is a longitudinal section of a modified form of tip, and Fig. 4 is an end view thereof. Fig. 5 is a longitudinal section of another tip, and Fig. 6 is an end view thereof.

In carrying out the invention, there is 50 provided a gas chamber 1 provided at its rear end with the outstanding hose attaching nipples 2, 3, 4, and 5, and a barrel or tubular member 6 is welded or otherwise attached to the other end of the chamber 1 to provide a fluid circulating chamber.

There is a partition 7 between the chamber 1 and barrel 6, and said partition is provided with a nipple 8 projecting into said chamber, and provided at one side with a 60 gas port or aperture 9. A gas tube or pipe 10 is disposed concentrically within the barrel 6 and has one end threaded or otherwise engaged within the nipple 8, so as to communicate with the chamber 1 by way of 65 the aperture 9, and an oxygen tube 11 extends through the tube 10, the nipple 8, and the chamber 1, and is attached to the nipple 4 for the connection of the oxygen hose. The gas hose is connected to the nipple 3 to 70 supply the acetylene or other gas into the chamber 1. The outer or forward end of the tube 11 projects out of the corresponding end of the tube 10, and the said end of the tube 10 is contracted and welded or otherwise secured, as at 12, to the tube 11. The tube 11 is provided with one or more apertures 13 adjacent the forward end of the tube 10, so that the gas can flow into the tube 11 by way of the apertures 13, thereby providing 75 the mixture which supports the needle flame.

Water, air or other suitable cooling fluid is supplied into the barrel 6 by means of a tube or pipe 15 extending through the barrel 80 6 and chamber 1 and connected at one end with the nipple 5, and the fluid is conducted out of the basal or butt end of the barrel 6 by means of a tube or pipe 14 having one end engaged through the partition 7 and 85 having its other end connected to the nipple 2. The fluid conducting hose are connected to the nipples 2 and 5, and any suitable fluid can be supplied into the tube 15.

The forward or outer end of the inlet tube 90 15 terminates within the conical tip member 16, whereby the fresh inflowing fluid will be supplied directly adjacent the tip, where the cooling effect is most needed. The member 16 has an outturned flange 17 resting 100 against the end of the barrel 6, and a union 18 is threaded upon the end of the barrel 6 and has a flange 19 overlapping the flange 17, whereby the member 16 is clamped in fluid tight engagement against the barrel. 105 The member 16 has a tubular portion 20 projecting inwardly from its apex and welded or otherwise secured, as at 21, to the end of the tube 11.

The tip 22 has a nipple 23 threaded or 110 otherwise removably engaged within the tubular portion 20, to provide the jet, vari-

ous tips being used interchangeably, and the tips can be removed from and applied to the member 16 without the necessity of detaching or interfering with any of the other parts.

Figs. 3, 4, 5 and 6 illustrate different forms of tips, for providing two jets. The tip 22' illustrated in Figs. 3 and 4 has a pair of branches or outlet apertures 24. The tip 22'' illustrated in Figs. 5 and 6 is chambered, and has a pair of outlet apertures 25. With these tips, a double jet is provided, and the apertures of the tips may be spaced different distances apart. The two-jet tip is of advantage, since two parts which are spaced apart can be heated simultaneously, prior to welding.

The blowpipe or torch is used in the ordinary manner for welding or similar purposes, and the cooling fluid in being supplied through the tube or pipe 15 will be directed from said tube into the tip member 16, thereby cooling the tip in the most effective manner. From the tip, the water flows back-wardly through the barrel 6, cooling the parts inclosed thereby, and flowing out by way of the tube 14. By using the cooling means, the blowpipe or torch can be handled more conveniently, the same being kept cool, and this also eliminates the tendency for the parts to warp or otherwise become distorted.

The present device can be used as a blow pipe, welding torch, cutting torch, or for kindred other purposes. When a multiple flame tip is used, the volume of heat is increased materially without an appreciable lengthening of the flame. Any suitable number of outlet apertures can be used, and with the multiple jet tip, the greatest amount of heat can be applied to the points where most needed.

Having thus described the invention, what is claimed as new is:

1. A device of the character described, embodying a fluid circulating barrel, a hollow tip member attached to one end thereof, a blowpipe inclosed within the barrel and connected to said member, the other end of the barrel having a fluid outlet, and a fluid supply pipe entering the last mentioned end of the barrel and extending to a point within said member.

2. A device of the character described, embodying a gas chamber having four hose at-

taching portions, a barrel connected to said chamber, there being a partition between said chamber and barrel, a tip member attached to the remote end of the barrel, a gas tube connected to said partition and extending within the barrel, said tube communicating with said chamber and one of said hose attaching portions providing a gas inlet for said chamber, an oxygen tube extending through the aforesaid tube and connected to another hose attaching portion and to the tip member, the oxygen tube having an aperture communicating with the first mentioned tube, a fluid outlet tube engaged through said partition and connected to another hose attaching portion, and a fluid supplying tube connected to the fourth hose attaching portion, extending through said partition and within the barrel to a point adjacent said tip member.

3. A device of the character described, embodying a chamber having four hose attaching nipples, one for supplying gas into said chamber, a barrel having one end attached to said chamber, a tip member attached to the other end of said barrel, there being a partition between said chamber and barrel having a nipple projecting into said chamber and provided at one side with an aperture, a gas tube having one end engaged within the last mentioned nipple, an oxygen tube extending through the gas tube, last mentioned nipple, and chamber, and connected to another of the first mentioned nipples, the oxygen tube being connected to the tip member, the respective end of the gas tube being secured to the oxygen tube, the oxygen tube having an aperture within the gas tube, a fluid discharge tube engaged through said partition and connected to another of the first mentioned nipples, and a fluid supplying tube connected to the fourth of the first mentioned nipples and extending through said chamber, partition and within the barrel and terminating adjacent said tip member.

In testimony that I claim the foregoing as my own, I have hereto affixed my signature in the presence of two witnesses.

GREEN B. WILSON.
